(57) **CLAIM**

The ornamental design for a barrel bushing wrench, as shown
and described.

DESCRIPTION

FIG. 1 is a front elevational view of a barrel bushing wrench
showing our new design.

FIG. 2 is a top elevational view of the barrel bushing wrench.

FIG. 3 is a left side elevational view of the barrel bushing wrench.

FIG. 4 is a right side elevational view of the barrel bushing wrench.

FIG. 5 is a bottom elevational view of the barrel bushing wrench.

FIG. 6 is a back elevational view of the barrel bushing wrench.

FIG. 7 is a front right side perspective view of the barrel bushing wrench.

FIG. 8 is a front perspective view of the barrel bushing wrench; and,

FIG. 9 is a back perspective view of the barrel bushing wrench.
